Des. 219,011

Patented Oct. 27, 1970

219,011

FUEL TANK

Richard L. Marushak, Downers Grove, George F. Schultz, Brookfield, and O'Neil J. Nichols, North Riverside, Ill., assignors to International Harvester Company, Chicago, Ill., a corporation of Delaware

Filed Aug. 11, 1969, Ser. No. 18,608

Term of patent 14 years

Int. Cl. D12—14

U.S. Cl. D14—3

FIG. 1.

FIG. 2.

FIG. 1

FIG. 2

FIG. 1 is a perspective view of the fuel tank;
FIG. 2 is a plan view of the fuel tank;
FIG. 3 is an elevational view of the fuel tank as viewed from the rear; and

FIG. 4 is an elevational view of the fuel tank as viewed from the front.

The portions shown in broken lines on the drawing are included for illustrative purposes only.

We claim:

The ornamental design of a fuel tank, substantially as shown and described.
